UNITED STATES PATENT OFFICE.

LEWIS LEONARD SCOTT, OF GLASFORD, ILLINOIS.

CHECK-ROW CORN-PLANTER.

SPECIFICATION forming part of Letters Patent No. 653,705, dated July 17, 1900.

Application filed April 9, 1900. Serial No. 12,205. (No model.)

To all whom it may concern:

Be it known that I, LEWIS LEONARD SCOTT, a citizen of the United States, residing at Glasford, in the county of Peoria and State 5 of Illinois, have invented a new and useful Check-Row Corn-Planter, of which the following is a specification.

My invention is an improved check-row corn-planter, the object of my invention being to provide a cheap, simple, and efficient check-row corn-planter which is adapted to operate without the use of a check-wire and anchors at the ends of a row and which may be readily adjusted to insure accuracy of its 15 operations.

My invention consists in the peculiar construction and combination of devices herein-after fully set forth, and pointed out in the claims.

20 In the accompanying drawings, Figure 1 is a top plan view of a check-row corn-planter embodying my improvements. Fig. 2 is a side elevation of the same, partly in section, on the line 2 2 of Fig. 1. Fig. 3 is a detail 25 perspective view of the markers, their supporting-bar, and connections. Fig. 4 is a detail transverse sectional view showing one of the operating-cams, a portion of the vertically-movable marker-bar, and one of the 30 guides and supports therefor. Fig. 5 is a similar view showing the driving sprocket-wheel, its connections, the hand-lever, and connections between the latter and the driving sprocket-wheel to throw said sprocket-wheel out of gear simultaneously with the 35 raising of the planting and marking mechanisms.

The main frame 1 of my improved corn-planter comprises the side bars 2, the cross-bar 3, connecting the rear ends of the same, and the arched cross-bar 4, near the front ends of said side bars. On the rear portion of said frame 1 is supported a seat 5 for the driver. An axle-shaft 6 is journaled in suitable bearings in the frame 1 and is provided 40 with supporting-wheels 7, one of said wheels being fast to said axle-shaft, whereby the latter is caused to rotate when the machine is drawn along. On one side of the frame 1 45 is a ratchet clutch member 8, which is keyed on the axle-shaft 6 and is adapted to engage a clutch member 9 on the inner side of a

driving sprocket-wheel 10 when said axle-shaft is rotated in one direction. Said clutch member 9 may be either secured to said driving sprocket-wheel 10 or formed integrally therewith, and the same also forms a ratchet-wheel 11. A spring 12 bears against the outer side of the sprocket-wheel 10 and moves the same inward normally on the axle-shaft to 60 keep the clutch member 9 thereof in engagement with the clutch member 8, fast on said axle-shaft, and thereby also normally lock the said sprocket-wheel on said shaft and cause it to rotate therewith. 65

The front end of the frame 1 is pivotally connected, as at 13, to a planter-frame 14, which is provided with the usual shoes or runners 15, the seed-tubes 16, the seed-hoppers 17, and a suitable seed-dropping mechanism, the latter being not shown, as it may be of any preferred type well known to those skilled in this art, and forms no part of my present improvements. The usual draft-tongue 18 is attached to the said planter-frame, and the rear end thereof extends to within a suitable distance of the axle-shaft, as shown. 70

A rock-shaft 19 is mounted transversely across the frame 1 at a point over the axle-shaft and in bearings 20. Said rock-shaft is provided at its center, in line with the draft-tongue, with a crank-arm 21, which is connected to said rear end of said draft-tongue by a coiled spring 22 or any other suitable 85 form of spring, and said rock-shaft is further provided with a rock-arm 23 and a hand-lever 24, the latter serving to enable said rock-arm to be readily turned in its bearings and being provided with a spring-depressed de- 90 tent 25, of usual form, which by engaging a sector-shaped rack-plate 26 on the frame 1 serves to lock said hand-lever and said rock-shaft at any desired adjustment. A cam-lever 27 bears against the inner side of the 95 sprocket-wheel 10 and is fulcrumed, as at 28, to the lower end of an arm or block 29, that depends from one side of the frame 1, and the inner end of said cam-lever is connected to the rock-arm 23 of rock-shaft 19 by a link 30. The outer end of the draft-tongue being attached to and supported from the collars of the team in the usual manner, it follows that 100 when the hand-lever 24 is turned rearwardly

the rock-arm 21 is turned upward, and being connected to the rear end of the draft-tongue, as hereinbefore described, the latter is raised at its rear end, thereby tilting or 5 inclining the frame 1 on the axle-shaft and raising the planter-frame, with its various parts and connections, entirely from the ground, thus adapting the machine to be driven from point to point or to turn at the 10 end of a row. Simultaneously with this elevation of the planting-frame the rock-arm 23 of the rock-shaft 19 by drawing upward on the link 30 turns the cam-lever so as to throw the driving sprocket-wheel 10 out of 15 engagement with the clutch member 8 on the axle-shaft, thereby causing said sprocket-wheel to be idle on said shaft, and hence causing the check-row planting and marking mechanisms to be thrown out of gear and 20 to cease to operate, as will be presently described.

A foot-lever or treadle 31 is pivotally connected and supported on one side of the frame 1, as at 32, and is provided with a pawl 33, 25 which is adapted to engage the upper side of the ratchet-wheel 11, fast with or forming an integral portion of the sprocket-wheel 10, and thus enabling the driver by motion of one foot on the said treadle or foot-lever to rotate 30 the said sprocket-wheel 10 in one direction, as will be understood, and for a purpose to presently appear.

A counter-shaft 34 is journaled in bearings on the front portion of the frame 1, and said 35 counter-shaft is provided with a pair of cam-wheels 35, which are fast thereon and near its ends, and a sprocket-wheel 36 is also fast on said counter-shaft. Said sprocket-wheel 36 is connected to the sprocket-wheel 10 by 40 an endless sprocket-chain 37, and hence rotary motion is imparted to said counter-shaft and said cam-wheels when the machine advances, and the said wheel 10 is fast on the axle-shaft, as will be understood. A pair of 45 vertical standards 38 rise from the frame 1 at points over the counter-shaft 34 and are provided with vertical guideways 39, in which operates a transversely-disposed vertically-movable marker-bar 40, the latter bearing on 50 the said cam-wheels 35 and being preferably provided with antifriction - rollers 41 to reduce friction between the same and the said cam-wheels. Said marker-bar has vertical openings 42, through which extend vertical 55 guide-rods 43, that are disposed in the guideways 39 and serve to sustain the said marker-bar against endwise movement. Springs 43^a on the upper portion of said guide-rods bear upon the upper side of the marker-bar, and 60 buffer-springs 44 on the lower portion of said guide-rods are disposed under said marker-bar and serve to reduce the concussion of the latter when the same drops as it is cleared by the cams of the revolving cam-wheels 35. 65 It will be understood from the foregoing and by reference to the drawings that the marker-bar by the rotation of the cam-wheels is al-

ternately raised and dropped, the springs 43^a, which bear on the said marker-bar, serving to increase the force of the downward movements of said marker-bar and the buffer-springs 44 serving to reduce the concussion of said marker-bar as it descends upon the cam-wheels.

On the ends of the marker-bar are pivoted 75 markers 45. Springs 46, which are secured to the ends of the marker-bar, engage the markers and normally sustain the same in vertical positions, while enabling said markers to turn rearward on the marker-bar in 80 order to clear obstructions which they may encounter in the field. A rock-shaft 47 is mounted in bearings 48 on the marker-bar and is provided at its ends with crank-arms 49, which are connected to scrapers 50, disposed on the rear sides of the markers and guided in guides 51, with which said markers are provided. At the center of the said rock-shaft is a crank-arm 52, against which bears a spring 53, which normally sustains the scrapers in the elevated positions shown in Fig. 3. A cord 54, attached to the arm 52, extends rearward to within an easy reach of the driver on the seat 5, and by drawing upon the said cord the driver, by partly rotating the rock-shaft 47, may cause the scrapers to descend on the rear sides of the markers and clear the latter of any trash that may be adherent thereto.

At the lower ends of the seed-spout 16 are 100 seed-valves 55, which are connected to arms 56 of a rock-shaft 57 by means of links 58. Said rock-shaft 57 is provided on its front side with an arm 59, to which is attached one end of a spring 60, the other end of said 105 spring being secured under the draft-tongue, and said rock-shaft is further provided with a rearward-extending crank-arm 61, which is engaged by a lever 62, fulcrumed, as at 63, on one side of the frame, the rear end of said 110 lever being disposed in the path of tappet-studs 64, carried by one of the cam-wheels 35. As the said cam-wheel 35 rotates the studs 64 thereof by successively engaging the lever 62 115 operate said lever and through the connections hereinbefore described operate the seed-valves 55, thereby causing the seeds discharged in the seed-tubes by the seeding mechanism to be deposited in the furrows in hills. The mechanism is so timed that the 120 marker-bar as the same becomes abreast of the hills drops, thereby causing the markers to enter the earth and mark the same in line with the hills, the marker on one side indicating the lines of the planted hills and on 125 the other side serving to indicate where the hills in the next unplanted furrows are to be seeded.

By means of the ratchet-wheel 11, the foot-lever or treadle 31, and the connections hereinbefore described the seed dropping and marking mechanisms may be adjusted, as may be required, from time to time and at the 130 end of the rows.

In Fig. 2 I have shown a tension device (indicated at 65) which may be employed to bear upon one lead of the endless sprocket-chain 37 and keep the same taut at all times.

5 Having thus described my invention, I claim—

1. In a check-row corn-planter, the combination with a vertically-movable marker-bar, pivoted markers thereon depending therefrom, and springs to normally sustain said pivoted markers in operative position in combination with means to operate said vertically-movable marker-bar, substantially as described.
- 15 2. In a check-row corn-planter, a vertically-movable marker-bar having depending markers at its ends, in combination with scrapers for said markers and means to operate said scrapers, substantially as described.
- 20 3. In a check-row corn-planter, a vertically-movable marker-bar having depending markers, in combination with scrapers for said markers, a rock-shaft connected to said markers, and means whereby said rock-shaft may be actuated, for the purpose set forth, substantially as described.
- 25 4. In a check-row corn-planter, the combination of a main frame supported on an axle, a master-wheel on said axle, a clutch to lock and unlock said master-wheel, a planter-frame
- 30 flexibly connected to the front end of the main frame, a draft-tongue attached to said planter-frame and extending rearward therefrom, a rock-shaft on the main frame, having arms
- 35 21, 23, a spring connection between the rear end of the draft-tongue and the arm 21, a cam-lever to operate the clutch, and a link

connecting said cam-lever to arm 23, all constructed and adapted to operate, substantially as described.

5. In a check-row corn-planter, the combination of the vertically-movable marker-bar having the depending markers, a shaft having cams to impart vertical movement to the marker-bar, an axle-shaft, a master-wheel on said shaft, clutched thereto and adapted to rotate in one direction independently thereof, connections between said master-wheel and the shaft having the cams, whereby the latter are rotated, and means to manually rotate said master-wheel independently of the axle-shaft, for the purpose set forth, substantially as described.

6. In a check-row corn-planter, the combination of a marker, a revoluble cam-wheel to 55 actuate the marker, said wheel having tappets, a seed-dropping mechanism, and a lever actuated by the tappets of the cam-wheel and connected to said seed-dropping mechanism, substantially as described.

7. In a check-row corn-planter, the combination with a vertically-movable marker-bar, guides therefor, springs bearing downward on said marker-bar, buffer-springs to arrest the descent of the marker-bar, and means to 65 actuate said marker-bar, substantially as described.

In testimony that I claim the foregoing as my own I have hereto affixed my signature in the presence of two witnesses.

LEWIS LEONARD SCOTT.
